VENTILATED CORRUGATED BOARD
CONTAINER

Norman F. De La Foret, Toledo, Ohio, assignor to
The Ottawa River Paper Company, Toledo,
Ohio, a corporation of Ohio

Application July 16, 1949, Serial No. 105,121

3 Claims. (Cl. 229—6)

1

This invention relates to containers, but more particularly to containers of corrugated sheet material. In certain instances, it is quite desirable, and even imperative, that the inside of containers be ventilated. This has, in the main, been accomplished by providing holes through the walls of these containers, but in some instances, this is decidedly impractical and unsatisfactory. Holes of this character which provide openings directly to the inside of the container enable dust, dirt and foreign particles to find their way inside so that the goods may be unsightly or otherwise rendered unsatisfactory.

Another objection to forming these holes in container walls is that they weaken the walls and in some instances that has militated against their use. This latter objection is particularly outstanding in the case of containers or cartons made of corrugated board of the usual type made up of a sheet of corrugated paper interposed between paper sheets or liners. It is accordingly a desideratum to provide a closed carton or container of corrugated board having breathing properties such that exchange of air between the inside and outside of the container may be indirectly effected without substantially weakening the container walls or exposing the inside of the container directly to the outside.

An object is to overcome the above difficulties and to produce a container of corrugated board perforated in such a manner as to permit exchange of air between the inside and outside of the container in an indirect manner and without appreciably weakening the walls of the container.

Another object is to provide a container of corrugated board having perforations so constructed and arranged as to enable the container to breathe and of such form and arrangement as to enable same to be efficiently and economically produced in quantity production.

Other objects and advantages of the invention will hereinafter appear, and for purposes of illustration but not of limitation, an embodiment of the invention is shown on the accompanying drawings, in which

Figure 1 is a view of a carton or container of corrugated board and provided with rows of apertures affording ventilation or breathing of the container;

Figure 2 is an enlarged transverse sectional view substantially on the line 2—2 of Figure 1;

Figure 3 is an enlarged transverse sectional view on the line 3—3 of Figure 1; and

Figure 4 is an enlarged vertical sectional view 55 on the line 4—4 of Figure 1.

2

The illustrated embodiment of the invention comprises a carton of corrugated board having side walls 10, bottom wall 11 and top closure flaps 12, the structure being old and well-known in the art and provides a closed container for receiving merchandise for shipping or storage purposes. Corrugated paper board is old and well-known in the art, and as shown on Figures 2 and 3, consists of an intermediate layer or ply 13 of relatively heavy corrugated paper, in this instance the corrugations extending vertically of the carton shown in Figure 1. On opposite sides of the corrugated sheet 13 are relatively thin paper sheets or liners, there being an inner liner 14 and an outer liner 15 which are adhesively and intimately adhered to the intermediate corrugated liner. Since the characteristics and properties of this corrugated board are well-known to those skilled in this art, further description is not considered necessary.

Before the corrugated board is folded to form the container, rows of relatively small holes or perforations 16 are formed in any suitable manner. On the outside of the corrugated board 25 and as shown on Figure 3, the holes not only pass through the outer liner sheet 15 but also through the corrugated sheet 13, but do not extend through the inner liner 14. The perforations 16 are arranged in a straight line and equi-distantly spaced from each other. Thus it will be observed that the perforations do not pass through the same portion of the corrugation in each instance, but for practical purposes it is sufficient that the perforation extend through the outer liner and the corrugated sheet. At the same time, it is just as important that these perforations do not pass through the inner liner 14, the reason for which will hereinafter appear. The number and spacing of these sheets of corrugations may be varied as desired. Preferably the row is interrupted at intervals thereby to militate against weakening of the side walls or panels of the carton.

Spaced above the rows of perforations 16 and 45 on the inside of the corrugated board are rows of perforations 17 which penetrate through the liner 14 and the corrugated sheet 13 but do not penetrate the outer liner 15. The row of perforations 17 may, in production, be formed concomitantly with the forming of the perforations 16 and generally speaking, a perforation 17 in the upper row corresponds to and is in alignment with a perforation 16 in the lower row of perforations so that a perforation 16 and a perforation 17 will each perforate the same hill or valley of one of the corrugations which in this in-

stance it will be understood extend vertically from top to bottom of the side walls of the carton.

Figure 4 illustrates by arrows the movement of air from the outside of the container or carton to the inside, air passing through a perforation 16 through the outer liner and corrugated sheet and into the channel formed between the corrugated sheet and the inner liner 14, thence upwardly and out through the corresponding 10 perforation 17 in the upper portion of the container wall. Manifestly, this air movement may be reversed allowing air from the inside to pass to the outside. This in effect enables the closed interior of the container or carton 10 to breathe, 15 the series of perforations on the inside and outside communicating through the channels formed by the intermediate corrugated layer and thus allowing exchange of air.

The advantages of this construction have been heretofore pointed out but may be briefly summarized as follows. The container is allowed to breathe but the dust and dirt from the outside can not find their way to the inside because of the tortuous air channels. The structure of the carton is not weakened to any appreciable extent nor are the perforations at all unsightly and, finally, the perforations of the above character can be formed in large scale production efficiently and economically and do not in any way interfere with the scoring of the board in the formation of the carton blank. This latter feature is shown in the drawings in which a portion of the row of perforations is on one side 35 of the score line and a portion on the opposite side.

It is to be understood that numerous changes in details of construction, arrangement and choice of materials may be effected without departing from the spirit of the invention especially as defined in the appended claims.

What I claim is:

1. A container comprising a body of corrugated sheet material having an intermediate ply provided with a series of elongate corrugations 45 interposed between and connected respectively

to relatively flat inner and outer liner plies, a perforation penetrating only the inner liner ply and the corrugated ply, and another perforation penetrating only the outer liner ply and the corrugated ply, said perforations penetrating the same corrugation by spaced points thereby to enable an exchange of air between the inside and outside of the container through said perforations and the channel formed by the respective corrugation.

2. A container comprising a body having side and end wall panels thereby to provide a closed package, said body being of corrugated paper and having an intermediate sheet provided with longitudinally elongate corrugations and inner and outer liners adhesively secured thereto, and a pair of spaced rows of inside and outside perforations, the perforations of each row penetrating only a single liner and corresponding corrugations thereby to provide tortuous air channels between the inside and outside of the container.

3. A container comprising a body having side and end wall panels thereby to provide a closed package, said body being of corrugated paper and having an intermediate sheet provided with longitudinally elongate corrugations and inner and outer liners adhesively secured thereto, and a pair of spaced rows of inside and outside perforations, the perforations of each row penetrating only a single liner and corresponding corrugations and each perforation having a lateral dimension less than the width of a corrugation, thereby to provide tortuous air channels between the inside and outside of the container.

NORMAN F. DE LA FORET.
